Primary Examiner — Mojtaba Tehrani(57) **CLAIM**

The ornamental design for a swim kickboard, as shown and described.

DESCRIPTION

FIG. 1 is a perspective view of a swim kickboard showing our new claimed design;

FIG. 2 is a right-side elevational view thereof, the left-side elevational view being a mirror image thereof;

FIG. 3 is a top plan view thereof;

FIG. 4 is a bottom plan view thereof;

FIG. 5 is a front elevational view thereof; and,

FIG. 6 is a back elevational view thereof.

The broken lines in the figures show portions of the swim kickboard that form no part of the claimed design.
